COMPACT DISHWASHER CABINET

Carl A. Peterson, Columbus, Ohio, assignor to Westinghouse Electric Corporation

Filed Mar. 15, 1972, Ser. No. 235,102

Term of patent 14 years

Int. Cl. D15—05

U.S. Cl. D49—1 A

FIG.1

FIG.5

FIG. 1 is a perspective view of a compact dishwasher cabinet embodying my new design;

FIG. 2 is a front elevational view thereof;

FIG. 3 is a side elevational view thereof;

FIG. 4 is a rear elevational view thereof; and

FIG. 5 is a top plan view thereof.

I claim:

The ornamental design for a compact dishwasher cabinet, substantially as shown and described.
